AUTOMOBILE TIRE

Loyd O. Dodson, Los Angeles, Calif., assignor to Vogue Rubber Company, Chicago, Ill., a corporation of Illinois

Filed Jan. 18, 1962, Ser. No. 68,355

Term of patent 14 years

(Cl. D90—20)

FIGURE 1 is a perspective view of a tire showing my new design, it being understood that the full line portion of the design is repeated throughout the circumference of the tire, the opposite side being substantially the same as that shown;

I claim:

The original design for an automobile tire, substantially as shown and described.
